(74) Attorney, Agent, or Firm — Foley & Lardner LLP

(57) **CLAIM**

The ornamental design for an ear clip, as shown and described.

DESCRIPTION

FIG. 1 is a rear perspective view of an ear clip; FIG. 2 is a rear elevation view of the ear clip; FIG. 3 is a front elevation view of the ear clip; FIG. 4 is left side elevation view of the ear clip; FIG. 5 is right side elevation view of the ear clip; FIG. 6 is a top view of the ear clip; and, FIG. 7 is a bottom view of the ear clip.

The broken lines represent portions of the ear clip that form no part of the claimed design. The dash-dot-dash line represents the boundary of the claimed region. The ear clip is shown with symbolic breaks. The appearance of any portion of the article between the symbolic break lines forms no part of the claimed design.

1 Claim, 7 Drawing Sheets(56)
